(57) **CLAIM**

We claim the ornamental design of the stitched plunger handle for luggage, as shown and described.

DESCRIPTION

FIG. 1 is a downward frontal rightward view of a stitched plunger handle for luggage according to our new design;
FIG. 2 is a downward frontal rightward prospective view of the handle;
FIG. 3 is a plan view of the handle;
FIG. 4 is a front view of the handle, a rear view is a mirror image of FIG. 4;
FIG. 5 is a bottom view of the handle; and,
FIG. 6 is a left elevational view of the handle, a right elevational view thereof being a mirror image of FIG. 6.
Broken lines throughout the Figs. Represent environmental structure and are not part of our Design.
